UNITED STATES PATENT OFFICE.

ARTHUR H. LAMBERT AND JOSEPH DUBOIS, OF BIDDEFORD, MAINE.

TOP-ROLL CLEAREER BOARD AND APRON CLIP FOR DRAWING FRAMES.

1,427,158.

Specification of Letters Patent. Patented Aug. 29, 1922.

Application filed March 23, 1921. Serial No. 454,738.

To all whom it may concern:

Be it known that we, ARTHUR H. LAMBERT and JOSEPH DUBOIS, citizens of the United States, residing at Biddeford, in the county 5 of York and State of Maine, have invented certain new and useful Improvements in Top-Roll Clearer Boards and Apron Clips for Drawing Frames, of which the following is a specification, reference being had 10 to the accompanying drawings.

This invention relates to spinning machines, and particularly to the clearers of the upper draft rolls of drawing frames.

These clearers as commonly constructed 15 consist of a board having staple-like wires attached at intervals to the bottom of the board facing the top rolls, there being an apron of flannel or like material attached to each pair of supporting wires. These 20 aprons rest lightly against the top of the rolls and as the rolls revolve the loose cotton is gradually collected by the outer surface of the apron. In the ordinary construction of these aprons, the staple-like 25 wires which are attached to the board have relatively straight legs which are driven into the wood to an extent deemed necessary by the person applying the staples and as a consequence not only are these staple- 30 like wires driven in different distances, but the staple-like wires oftentimes are accidentally forced into the board to a greater extent than desired and as a consequence the aprons would get out of proper adjustment.

One of the objects of our invention is to 35 prevent this maladjustment of the supporting wires of the aprons by so forming the wires that they cannot be forced in beyond a predetermined amount either when they are 40 initially driven into the board or in actual use so that each apron is supported a predetermined distance from the board and all of the aprons of the clearer board are supported at the same distance from the face 45 of the board and, therefore, have the same contact with the leather-covered top rolls.

A further object is to so mount the staple-like wire holding members upon the front of the board that they are lower than the 50 wire members at the rear of the board, thus causing all roving yarn to run upon the roll provided for the same and preventing the roving yarn from winding upon the leather-covered top roll which tends to cause the 55 leather on these top rolls to become worn and torn.

Other objects will appear in the course of the following description.

Our invention is illustrated in the accompanying drawings, wherein:—

Figure 1 is a fragmentary vertical section through a drawing frame of ordinary construction, showing our improved clearer board applied thereto;

Figure 2 is a transverse section of the clearer board;

Figure 3 is a fragmentary longitudinal section of the clearer board;

Figure 4 is an under side plan view of the clearer board;

Figure 5 is an elevation of the staple;

Figure 6 is a face view of the upper and lower drawing rolls and a portion of the board.

Referring to these drawings, 10 designates the top roll clearer board of a spinning frame and 11 designates generally the series of top rolls, while 12 designates the bottom draft rolls. This top board is supported in any suitable manner upon the top rolls, 80 and it will be understood that these rolls are to be supported in the ordinary roller stand and provided with the usual bearings for the front roll, the middle roll and the back roll. The top rolls are of the usual 85 form and we have illustrated what is known as a single boss roll. Each of these rolls 11 is formed with trunnions 13 at its ends, a middle reduced portion 14 and a pair of leather-covered, cylindrical portions 15 be- 90neath which the yarn passes, the yarn passing between the fluted lower draft rolls 12 and the leather-covered rollers 11. So far, the parts which we have described are the parts commonly found in the drawing 95 frames of spinning machines, it being understood, of course, that ordinarily on the bottom of the clearer board 10 there are disposed the transversely extending aprons of flannel which rest upon the top rolls 11 and 100 bear upon the leather faces of these top rolls.

The improvement in the top board which we have devised consists in forming the top board at its forward edge with a downwardly extending flange 16 which extends downward about $\frac{1}{4}$ " below the level of the top board. This top board is cut out at intervals, as at 17, to support the bearings for the rolls and is longitudinally grooved on 110 its under face, as at 18, as is usual in top boards to accommodate these bearings. The

aprons 19 are endless and formed of flannel, as is usual, but these aprons are supported by supporting clips or staples of a peculiar form, one of which staples is illustrated in Figure 5. The wire from which each staple is made is bent to form a cross bar 20 having a width approximately the same as the width of the front, then the wire is bent angularly and inward, as at 21, and then 10 the wire extends at right angles to the cross bar 20 to form the two legs or shanks 22 which are driven into the wood. It will be seen that the shoulders formed by the bends 21 prevent the staple from being driven into 15 the wood to more than a certain extent and that they, therefore, space the cross bar 20 accurately from the face of the clearer board.

It will also be seen that one series of these 20 apron supporting staples is driven into the flange 16 so that these staples are thus lower than the staples which are driven into the rear margin of the board so that the aprons supported on the staples have their lower 25 surfaces inclined downward and forward generally speaking relative to the plane of the under face of the clearer board when not applied to the top rolls 11. By forming the board with the depending flange 16 and 30 attaching the apron to staples fixed in this flange, the inner flight of the apron is supported at all times in spaced relation to the under surface of the clearer board and does not come in contact with this clearer board, 35 as it does in the ordinary construction of clearer board. The staples cannot be forced any further inward than the shoulders 21 and these shoulders thus form a stop for the workman who drives the staples to prevent him from accidentally driving the staple 40 deeper than it should be and thus the cross bar 20 of all the staples are disposed a uniform distance from the board and, therefore, holds all the aprons a uniform 45 distance from the inner face of the board in spaced relation to the face of the board.

It will further be noted that this clearer 50 board is longer at the front and lower down at the front than the ordinary clearer board, that is our improved board will come forward above the center and lower down in front than the old board. When the clearer board is in use and its weight is resting upon the apron, that portion of the apron which 55 is rearward of the front roll is parallel with the board, but from the top center of the front roll the apron curves downward and forward over the face of the front roll or has a downward drop of about $\frac{3}{8}$ ", which causes the cott 60 or apron to extend down over the center of the top roll, thereby preventing the sliver or end when it breaks from running up and around the top roll. It is in order to provide for this curvature of the forward end of the 65 apron that the space between the forward

end of the apron and the inner face of the clearer board is greater at the front than it is at the back. Furthermore, the accumulation of waste on the front is always in front of the back and middle rolls and in the rear 70 of the front roll and as the front roll travels at a greater rate of speed, it will be obvious that it requires a greater space in front to allow for an accumulation of waste. Our construction prevents the end when it breaks 75 from going up and around the top roll and forces it to go down around the scavenger roll that is ordinarily provided for that purpose on a spinning frame. This construction prevents the leather covering of the 80 top rolls from becoming torn, worn and cut. This means the elimination of a relatively large upkeep cost, as our invention will save these rolls from being destroyed.

We claim:—

1. A clearing board for the draft rolls of drawing frames having pairs of staples driven into the under face of the board at the opposite edges thereof, said staples being formed with shoulders limiting the extent 90 to which the staples may be driven into the board said shoulders engaging the under face of the board, and aprons supported by said staples.

2. The combination with the clearing 95 board for the top rolls of drawing frames, of a series of staples on the opposite side edges thereof and depending therefrom, each of said staples being bent to form a cross bar and inwardly extending shanks 100 from opposite ends of the cross bar, each of said shanks being bent adjacent the cross bar to form a stop limiting the inward movement of the staple into the board, the shanks being inserted into the board with their shoulders bearing against the under face of the board.

3. The combination with the clearing board for the top rolls of drawing frames, of a series of staples driven into the board on 110 the opposite side edges thereof and depending therefrom, the material forming said staples being bent at right angles to the cross bar at the ends of the cross bar, then being bent approximately parallel to the cross bar 115 and toward each other to form stops, then extending at right angles to the cross bar to thereby form shanks, said shanks being inserted into the clearer board with the stops bearing against the under face of the board, 120 said stops thus limiting the extent to which the shanks may be driven into the board, and aprons mounted upon said shanks.

4. A clearer board for the top rolls of drawing frames having a depending flange 125 upon its forward edge, forward staples driven into this flange and depending below the same, rear staples driven into the rear edge of the member and depending below the same, and aprons carried by said staples and 130

disposed beneath the under face of the board, all of the staples being of equal length and having shanks formed with stops, the stops bearing against the under face of the board and holding the staples on the forward edge of the board and on the rear edge of the board in the same spaced relation to the under face of the board.

5. A clearer board for the top rolls of
10 drawing frames and aprons mounted upon the under face thereof, the aprons at their forward ends being held spaced a greater

distance from the face of the board than at their rear ends and the distance between the forward and rear ends of the aprons being 15 greater than the distance between the forward and rear faces of the forward and rear rolls respectively whereby to cause the apron to extend down over the front roll.

In testimony whereof we hereunto affix 20
our signatures.

ARTHUR H. LAMBERT.
JOSEPH DUBOIS.
